POWER DRIVE FOR TOOLS

Robert F. Krueger and John L. Krueger,
Detroit, Mich.

Application April 26, 1940, Serial No. 331,742

4 Claims. (Cl. 74—52)

Our present invention relates in general to improved means for converting motion from one form into another, and relates more specifically to improvements in the construction and operation of mechanism for transforming continuous rotary motion into uniform reciprocating movement especially adapted for the propulsion of tools such as files.

Generally defined, an object of our present invention is to provide a new and useful motion transforming mechanism especially adapted to convert continuous rotary motion into uniform reciprocating movement.

Some of the more specific objects of our invention are as follows:

To provide an improved power drive for reciprocable tools such as files, which is simple and compact in construction, and highly efficient in use.

To provide an improved motion converting assemblage which is capable of effectively transforming relatively high speed rotary motion into relatively slow and long stroke reciprocating movement or motion of translation.

To provide an extremely durable and compact driving assembly for portable tools, which can be conveniently manipulated without danger to the operator.

To provide an improved fluid pressure operated driving rig for reciprocable tools which require relatively smooth and uniform motion of translation during normal operation.

To provide a portable tool drive which may be confined within the manipulating handle, which requires minimum attention, and which may be manufactured and operated at moderate cost.

To provide a relatively simple and exceedingly compact motion transferring and converting mechanism which is susceptible of diverse applications.

These and other specific objects and advantages of the invention will be apparent from the following detailed description.

A clear conception of an embodiment of the features constituting our present improvement, and of the mode of construction and of manipulating a power drive for reciprocable tools built in accordance with the invention, may be had by referring to the drawings accompanying and forming a part of this specification wherein like reference characters designate the same or similar parts in the various views.

Fig. 1 is a part sectional side view of an air

motor driven portable file, with the guide plate removed;

Fig. 2 is a central vertical section through the assemblage of Fig. 1, taken along the line 2—2;

Fig. 3 is a transverse vertical section through the driving and motion converting assembly of Fig. 2, taken along the irregular line 3—3;

Fig. 4 is a horizontal section through the assemblage of Fig. 2, taken along the line 4—4;

Fig. 5 is another horizontal section through the assemblage of Fig. 2, taken along the line 5—5;

Fig. 6 is a fragment of the file carrying slide and of a file, these elements being detachably connected by a jaw chuck;

Fig. 7 is a side view similar to that of Fig. 1, and showing the file carrier in extreme forward position;

Fig. 8 is another similar view, showing the file carrier moved back to mid-position;

Fig. 9 is still another similar view showing the file carrying slide moved rearwardly to its extreme position; and

Fig. 10 is an additional similar view, showing the file carrier moved forwardly to mid-position.

While our invention has been shown and described herein as being embodied in a rotary air motor driven assemblage especially adapted to reciprocate a file or the like, it is not our desire or intent to thereby unnecessarily restrict the scope or utility of the motion converting mechanism.

Referring to the drawings, the improved portable tool driving assemblage illustrated therein, comprises in general a rotary air-operated propelling motor having a rotor 14 mounted on a drive shaft 15 and provided with blades 16 cooperating with an enclosing casing or housing 17; a pinion 18 carried by an end of the rotary shaft 15 and coacting with a rotary internal gear 19 secured to one end of a driven shaft 20 journaled in a bearing 21 carried by another casing 22; a crank 23 formed integral with the opposite end of the driven shaft 20 and having a crank pin 24 upon which a gear 25 is rotatably supported; a fixed annular toothed element or rack 26 secured to the casing 22 and having internal teeth 27 with which the teeth of the gear 25 have rolling coaction; a second crank 28 rigidly secured to the gear 25 and having a crank pin 29 coacting with an opening 30 formed in a reciprocable bar or slide 32; a guide member 33 secured to the casing 22 and having a rectilinear guide-way 34 within which the slide 32 is reciprocable; and a chuck 35 carried by an end of the

slide 32 and adapted to firmly but detachably secure a tool such as a file 36, to the slide bar 32.

The air-operated propelling motor has a circular displacement chamber 37 disposed eccentrically of the rotor shaft 15 and within the housing 17, and the rotor blades 16 are slidable in radial slots 38 in the rotor 14 and are constantly urged toward and into contact with the annular wall of the chamber 37 by means of helical compression springs 39. The rotor confining chamber 37 is enclosed by a removable closure plate or cover 40 and has a tangential air inlet opening 41 and an air exhaust opening 42, as shown in Fig. 5. The inlet opening 41 communicates with a supply pipe 43 having a control valve 44 therein, and adapted for attachment to a flexible air supply hose not shown; and the drive shaft 15 may be journalled in self-lubricated bearings 45, 46 carried by the housing 17 and cover 40 respectively, and may be secured to the rotor 14 by means of a key 47. The cover 40 and housing 17 may be detachably secured to each other and to the casing 22 by means of screws 48; and the pinion 18 which is carried by the drive shaft 15, is located within a chamber 49 formed within the casing 22 and in which the internal gear 19 is located.

The internal gear 19 with which the pinion 18 coacts, may be formed sufficiently heavy to provide desirable flywheel effect, and since the pinion 18 has relatively small diameter as compared to the pitch diameter of the gear 19, the latter will naturally rotate at considerably slower speed. The gear 19 may be firmly attached to the driven shaft 20 by a nut 50, and the bearing 21 may also be of a self-lubricating type although lubricant may be confined within the chamber 49. As previously indicated, the crank 23 is formed integral with the shaft 20; and the gear 25 which is rotatably supported by the crank pin 24, has a pitch diameter approximately one-half as great as the pitch diameter of the annular stationary rack 26, so that the rack has twice the number of teeth 27 as has the gear 25. The crank 28 is firmly attached to the revolving gear 25, and by virtue of the fact that this gear 25 coacts with the teeth 27 of the fixed annular rack 26, the crank pin 29 will revolve about the axis of the crank pin 24 but in a direction opposite to the direction of revolution of the crank 23, during rotation of the shaft 20. The ratio of the gear teeth to the rack teeth 27 is however such, that the rotation of the gear 25 caused by the rack teeth 27, will cause the axis of the crank pin 29 to traverse a rectilinear path in the central plane of the guideway 34, at all times.

The gear 25 is revolvable within a chamber 51 in which the rack 26 is also confined, and the crank pin 29 has a snug fit in the opening 30 of the slide 32. The slide 32 is freely reciprocable in the guideway 34 of the guide member 33, and this member may be detachably secured to the casing 22 by means of screws 52. The chuck 35 which is carried by the end of the reciprocable slide 32, comprises tapered jaws 53 and a clamping collar 54 coacting with the jaws 53 and with screw threads 55 formed on the slide 32. The jaws 53 are adapted to firmly engage the shank 56 of a file 36 or other tool which is to be reciprocated, and the housing 17 and casing 22 serve as a handle for effecting manipulation and transportation of the portable tool assemblage.

During normal operation of the improved port-

able tool the control valve 44 may be set to admit more or less air under pressure to the chamber 37 through the tangential inlet 41, thereby causing the rotor 14 to revolve at relatively high speed and to rotate the shaft 15 and pinion 18 at corresponding speed. The rotation of the pinion 18 is imparted to the shaft 20 through the internal gear 19, but at considerably reduced speed; and as the shaft 20 revolves the crank 10 23, the crank pin 24 and gear 25 are caused to traverse an orbital path with the teeth of the gear rolling along the internal teeth 27 of the fixed rack 26. While the gear 25 is being carried about the axis of the shaft 20 in a clockwise direction as viewed in Figs. 1 and 7 to 10 inclusive; due to its coaction with the rack teeth 27, this gear 25 will simultaneously rotate about the axis of the crank pin 24 in a counter-clockwise direction, thereby causing the slide driving crank pin 29 to traverse a rectilinear path and to reciprocate the slide 32. The total travel of the pin 29 is approximately equal to the pitch diameter of the fixed rack 26, and when the gear 25 is positioned as in Fig. 7 the pin 29 will be 15 to the extreme left, whereas shifting of this gear to the position shown in Fig. 9 will position the pin 29 to the extreme right. When the gear 25 is in either of the intermediate positions shown in Figs. 8 and 10, the crank pin 29 will be in 20 mid-position with its axis disposed in the central plane of the slide 32. In this manner, the slide 32 will be reciprocated through a relatively long stroke and with uniform speed, with the aid of a crank 23 having relatively short radius of 25 swing.

From the foregoing detailed description, it will be apparent that our invention provides a motion transforming mechanism adapted to convert relatively high speed continuous rotary motion into uniform reciprocating movement having a relatively long stroke, and that the improvement is especially useful for the purpose of driving tools such as files or the like. The assemblage is obviously extremely simple, compact and highly efficient, since no slippage can occur between the driving motor and the reciprocating slide 32. The entire assemblage can be conveniently housed within a relatively compact casing which can be utilized as a manipulating handle for the tool, and all parts of the assemblage are effectively protected against possible damage while still being readily accessible for inspection. Although the improved mechanical movement is especially useful for the purpose of driving tools such as files, it can also be utilized for any other purpose where it is desired to secure relatively long stroke reciprocation at uniform speed and where the driving power is derived from a rotary source. The assemblage can also be manufactured and operated at moderate cost and requires little attention after proper construction and assembly thereof. The invention has proven highly successful and satisfactory for the purpose of driving tools such as files, and because of the compactness of the driving mechanism, tools of this type can be operated in any desired position.

It should be understood that it is not desired to limit this invention to the exact details of construction or to the precise mode of use, herein shown and described, for various modifications within the scope of the claims may occur to persons skilled in the art.

We claim:

1. In combination, a casing having a fixed

central bearing and a fixed rectilinear guide extending approximately equidistant across the axis of said bearing, a rotary shaft journalled in said bearing and having thereon a crank pin which is revolvable about said axis, a gear journalled on said pin and having thereon another crank pin revolvable about the axis of rotation of the gear and movable along said fixed guide, a fixed rack for rotating said gear about its own axis, and a slide reciprocable along said guide by said other crank pin.

2. In combination, an approximately cylindrical casing having a fixed central bearing and a fixed rectilinear guide at one end of the casing and extending across and approximately equidistant on opposite sides of said bearing, a rotary shaft journalled in said bearing and having at one end thereof a crank pin revolvable about the axis of rotation of the shaft, a rotary motor coacting with the opposite end of said shaft to rotate the latter, a gear journalled on said pin and having an eccentric bearing portion movable along said fixed guide, an annular toothed element secured within said casing coacting with said gear to rotate the same about its own axis, and a member reciprocable along said guide by said bearing portion.

3. In combination, an approximately cylindrical casing forming a handle and having therein a central bearing and a fixed transverse guide at one end of said bearing and projecting approximately equidistant on opposite sides thereof, a rotary shaft journalled in said bearing and hav-

ing one end provided with an eccentric crank pin, a rotary motor housed within and near the central axis of said casing and cooperating with the opposite end of said shaft to rotate the same within said bearing, a gear journalled on said crank pin and having an eccentric projection extending into said fixed guide, an annular rack fixed within said casing and coacting with said gear to rotate the latter, and a reciprocable slide coacting with said fixed guide and with said gear projection.

4. In combination, an approximately cylindrical casing forming a handle and having therein a central bearing, a fixed transverse rectilinear guide spanning said bearing at one end of the casing and extending approximately equidistant on opposite sides of the bearing, a rotary shaft journalled in said bearing and having one end provided with an eccentric crank pin and its opposite end provided with an internal gear, a rotary propelling motor housed within said casing near the central axis of said bearing and having a pinion drivingly engaging said internal gear, a spur gear journalled on said crank pin and having an eccentric pin projecting therefrom into said fixed guide, an annular rack fixed within said casing and coacting with said spur gear to rotate the latter, and a reciprocable slide coacting with said fixed guide and with said eccentric gear pin.
